UNITED STATES PATENT OFFICE.

ROBERT H. ROLFS AND HARRY J. ROLFS, OF WEST BEND, WISCONSIN, ASSIGNEES TO
AMITY LEATHER PRODUCTS CO., OF WEST BEND, WISCONSIN.

KEY CASE.

Application filed May 8, 1925. Serial No. 28,842.

To all whom it may concern:

Be it known that we, ROBERT H. ROLFS and HARRY J. ROLFS, both citizens of the United States, and residents of West Bend, 5 in the county of Washington and State of Wisconsin, have invented certain new and useful Improvements in Key Cases; and we do hereby declare that the following is a full, clear, and exact description thereof.

10 This invention relates to key cases.

The invention is particularly directed to a key case in which a back is provided with a pair of overlapping flaps adapted to enclose the keys under normal conditions, and 15 adapted to permit opening thereof and the projection of a key from the case when it is needed.

Objects of this invention are to provide a key case in which a very strong and simple 20 construction of retaining means for the hooks is provided, in which the retaining means is formed of one unitary member adapted to receive a plurality of hooks and 25 permit free motion thereof, and in which provision is made for an identification card if desired.

Further objects are to provide a key case in which the hook attaching means is formed of leather or other sheet material and in 30 which the utmost cheapness and simplicity of construction is attained.

An embodiment of the invention is shown in the accompanying drawings, in which:—

Figure 1 is a view of the key case opened 35 out flat.

Figures 2 and 3 are fragmentary details of further forms of the invention.

Referring to the drawings, it will be seen that the key case comprises a main body portion 1 provided with foldable flaps 2 and 3 equipped with a snap fastening means 4.

The element for retaining the hooks in place consists of a sheet of leather or other suitable flexible sheet material. This strip 45 is stitched along its upper edge, as indicated at 6, and along one side edge, as indicated at 7, from one end to the other. It is provided with a line of stitching 8 which extends part way down the other side edge.

50 A bottom line of stitching 9 secures the lower edge of the strip in place and an intermediate line of stitching 10 is positioned trans-

versely of the strip. The strip is provided with a plurality of cutouts 11 which define free straps 12.

The key hooks 13 may be of the usual construction and are connected by means of swivel joints 14 with eyelets or rings 15. The rings are adapted to be looped about the connecting straps 12, as illustrated in Figure 1, and to thus retain the hooks in place while permitting a limited motion of the rings 15 to thus facilitate manipulation of the hooks.

It is to be noted that the lower portion 65 of the sheet 5 is provided with a cutout 16 within which is positioned a piece of transparent celluloid or similar material 17. This celluloid is retained in position by the stitching 7, 9 and 10. An additional line of stitching 18 extends through the celluloid strip and the edge of the sheet 5, but does not extend through the body 1 of the key case. This leaves an opening for the insertion of an identification card if desired. 75

In the form shown in Figure 2, the body portion 19 is provided with an integral flap 20 at its upper edge which is folded over and stitched by means of marginal rows of stitching 21 to such body portion. It is provided with cutouts 22 and with tongues 23 similar to the cutouts 11 and tongues 12, previously described.

In the modified form shown in Figure 3, the body portion 24 is provided with a separate strip or sheet 25 which is in turn provided with horizontal cutout portions 26 defining horizontal free straps 27.

It is to be understood that in any of the forms illustrated, the attaching flap may be 90 formed either integral or separate from the body portion, as desired.

It will be seen that a key case has been provided which may be very cheaply manufactured, which does not require attaching cords, pintle pins, rivets or other expensive construction, but which furnishes the attaching means for the key hooks in a very simple and cheap manner.

Further, it will be noted that the key case 100 may be very quickly manufactured at a minimum of expense particularly in view of the fact that the cutouts for the attaching flap may be stamped at one operation and

the entire attaching flap secured in position by a simple stitching operation.

Although the invention has been described in considerable detail, it is to be understood that the invention may be variously embodied and is, therefore, to be limited only as claimed.

While we have shown a similar cutout forming tongues as a single piece, obviously the strips forming the tongues may be reinforced to strengthen the material where strain occurs.

We may in some instances, without departing from the spirit of the invention, utilize a metallic flap with the tongues folded over to form loops for the key hooks.

We claim:

1. A key case comprising a body portion having foldable end flaps, a sheet of flexible material stitched to said body portion along its marginal edges and having a portion thereof free from said body portion, a relatively large cutout formed adjacent the unattached portion, a transparent member positioned rearwardly of said cutout and providing an identification card pocket, said sheet of material having a plurality of regularly spaced cutouts of smaller size than said first mentioned cutout, and defining tongues therebetween, and key hooks provided with

rings, said rings being looped around said tongues.

2. A key case comprising a body portion having foldable flaps, a rectangular sheet of flexible material stitched along its bottom, one side edge, and top to said body portion and stitched along an intermediate line between its top and bottom edges transversely to said body portion, the unstitched side of said flap being stitched partially from the upper line of stitching to the intermediate line thereof, a plurality of vertically extending tongues formed integrally with the upper portion of said sheet and stopping short of the top line of stitching and the intermediate line of stitching, a transparent member stitched to the free portion of said sheet of material, said sheet of material having a cutout in front of said transparent portion, and a plurality of key receiving members having ring portions looped about said tongues and free to slide vertically upon said tongues.

In testimony that we claim the foregoing we have hereunto set our hands at West Bend, in the county of Washington and State of Wisconsin.

ROBERT H. ROLFS.
HARRY J. ROLFS.
